Primary Examiner — Rachel A. Voorhies*Assistant Examiner* — Benjamin D. Wannemacher(57) **CLAIM**

The ornamental design for a ratchet wrench, as shown and described.

DESCRIPTION

FIG. 1 is a front-right-top perspective view of the ratchet wrench showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view from another angle of view thereof.

The broken lines of the ratchet wrench in FIGS. 1-8 are illustrative of portions of the ratchet wrench that form no part of the claimed design.

1 Claim, 8 Drawing Sheets(56)
